Morsell, Keeney & Morsell,
ATTORNEYS.

UNITED STATES PATENT OFFICE.

RUSSELL M. PUTNAM, OF OCONTO FALLS, WISCONSIN.

RIPPLE AND BUBBLE ELIMINATOR.

Application filed July 11, 1925. Serial No. 43,046.

To all whom it may concern:

Be it known that I, RUSSELL M. PUTNAM, a citizen of the United States, and resident of Oconto Falls, in the county of Oconto 5 and State of Wisconsin, have invented new and useful Improvements in Ripple and Bubble Eliminators, of which the following is a description, reference being had to the accompanying drawings, which are a part 10 of this specification.

This invention relates to improvements in ripple and bubble eliminators, more particularly adapted for use with paper making machines.

15 In the manufacture of paper, considerable trouble is experienced, due to the fact that bubbles form in the thin sheet of pulp which is fed from the pulp vat to the Fourdrinier wire screen endless belt, with 20 the result that the paper formed is provided with thin spots. Furthermore, the pulp, in passing from the vat to the screen, is apt to ripple, and the paper will therefor be of uneven thickness.

25 It is one of the objects of the present invention to overcome the before mentioned objectionable features and provide a means for breaking up the bubble formation and smoothing out the ripples so that a more 30 even paper results which is free from thin spots.

A further object of the invention is to 35 provide a ripple and bubble eliminator which may be easily attached to ordinary machines now in use and which may be adjusted to fit machines having Fourdrinier screens of different widths.

40 A further object of the invention is to provide a ripple and bubble eliminator which may be easily adjusted to form paper of different thicknesses.

45 A further object of the invention is to provide a ripple and bubble eliminator which is of simple construction, is strong and durable, and is well adapted for the purpose described.

With the above and other objects in view, 50 the invention consists of the improved ripple and bubble eliminator and its parts and combinations as set forth in the claims, and all equivalents thereof.

In the accompanying drawing in which 55 the same reference characters indicate the same parts in all of the views:

Fig. 1. is a top view of the improved ripple and bubble eliminator shown con-

nected to a portion of a pulp vat and paper making machine;

Fig. 2 is an end view of the eliminator and a transverse sectional view of the pulp 60 vat; and

Fig. 3 is a transverse sectional view of the eliminator taken on line 3—3 of Fig. 1.

Referring to the drawing, the numeral 5 indicates a portion of a pulp vat which is 65 provided with a vertically adjustable gate or door 6 for controlling the flow of pulp to the Fourdrinier screen endless belt 7 mounted on a roller 8 and forming part of a paper machine. The improved ripple and 70 bubble eliminator 9 is provided with U-shaped brackets 10 which are adapted to hook over the gate 6 and are adjustably connected thereto by bolts 11 and 12. The bolts 11 are threaded horizontally through 75 the inner portions of brackets and impinge against the inner side of the gate 6 to clamp the brackets tightly to the gate while the upper bolts 12 are threaded vertically through the upper portions of the brackets and bear 80 on top of the flange 6' of the gate 6 to adjust the height of the brackets before clamping the brackets to the gate. Nuts 11' and 12' are mounted on the bolts 11 and 12 to 85 lock the same against accidental turning when in adjusted position.

The outer end portions of the bracket have openings for receiving a hinge pin rod 13 and upon this rod are pivotally mounted hinge leaves 14, 15 and 15'. The leaves 15 and 90 15' are also slidably mounted on the rod 13 to permit adjustment of the parts while the leaf 14 extends on each side of the center bracket 10' and is only hingedly movable on said rod. The leaf members 15 and 15' 95 are connected to the upper portions of floating members or plates 16 and 17, respectively by rivets 18. The said plate 16 has a lower flat surface and overlaps the plate 17 and is provided with upturned front and rear 100 flanges 18. The floating member or plate 17 also has a lower flat surface and is provided with upturned and downwardly folded flanges 19 to form groove ways 20 into which the flanges 18 slidably extend so that the length of the floating member can be 105 adjusted to fit the width of the Fourdrinier screen. In adjusting the plates, the eyed portions 21 of the hinge leaves 15 and 15' slide on the rod or pin 13 while the central leaf 14 is maintained in its position as before mentioned. Cotter pins 22 extend

through end portions of the pivot pin rod 13 to prevent the accidental removal of the plates 16 and 17. The said plates are held in adjusted position by means of a bolt 23 which extends through elongated slots 24 formed in the overlapped portions of the plates and in the central hinge leaf 14. The bolt also extends through an elongated washer 25 mounted on the central leaf 14 and is provided with a nut 26 for clamping the parts together. The bolt 23 is provided with an elongated head 23' which in connection with the elongated washer 25, covers the elongated slots 24 and prevents the entrance of pulp therein. The portion of the bolt 23 extending through the elongated slots is flattened and of a width corresponding to the width of the slots as indicated by the numeral 26 to prevent the bolt turning in the slots, while the central portions 24' of the slots are of the same diameters as the bolt 23 to permit the removal of said bolt.

In use, the parts are mounted on the pulp vat gate as shown, with the plates or members 16 and 17 resting or floating on the surface of the thin film of pulp flowing from the vat and being carried by the Fourdrinier belt, and as the pulp travels beneath the floating member and in engagement therewith, the air bubbles will be broken up and the spaces caused thereby will be filled with the pulp. The ripples or undulations of the pulp will also be leveled by engagement with the floating member so that the resultant paper will be smooth and free from thin spots.

From the foregoing description it will be seen that the ripple and bubble eliminator is of very simple construction and can be easily attached to the ordinary paper making machine, and when not in use can be swung upwardly against the gate.

What I claim as my invention is:

1. The combination with a paper making machine including a pulp vat and an endless belt, of a ripple and bubble eliminator therefor, comprising bracket means for connection with the pulp vat, and a floating member pivotally connected to the bracket means and positioned above the endless belt and engaging the pulp carried thereby.

2. The combination with a paper making machine including a pulp vat and an endless belt, of a ripple and bubble eliminator therefor, comprising bracket means for connection with the machine, and a floating member hinged to the bracket means and positioned above the endless belt and resting on the sheet of pulp carried thereby to break up the bubbles and smooth out the ripples of the pulp discharged from the vat and on to the belt.

3. The combination with a paper making machine including a pulp vat and an endless belt, of a ripple and bubble eliminator

therefor, comprising bracket members adjustably secured to the gate of the vat, and a floating member hinged to the bracket members and positioned above the endless belt and resting on the surface of the sheet of pulp carried thereby to break up the bubbles and smooth out the ripples of the pulp discharged from the vat and on to the belt.

4. The combination with a paper making machine including a pulp vat and an endless belt, of a ripple and bubble eliminator therefor, comprising U-shaped bracket members adjustably secured to the gate of the vat, and floating plates pivotally connected to the brackets and adjustably connected to each other, said floating plates positioned above the endless belt and resting on the surface of the sheet of pulp carried by the belt to break up the bubbles in the pulp discharged from the vat and on to the belt.

5. The combination with a paper making machine including a pulp vat and an endless belt, of a ripple and bubble eliminator therefor, comprising a U-shaped bracket extending over the gate of the vat and having means for connection with the gate, a rod carried by the outer lower end portion of the bracket, overlapped plates pivotally connected to the rod and resting on the pulp carried by the belt, and means for adjustably fastening the overlapped plates together.

6. The combination with a paper making machine including a pulp vat and an endless belt, of a ripple and bubble eliminator therefor, comprising a U-shaped bracket extending over the gate of the vat and having means for connection with the gate, a rod carried by the outer lower end portion of the bracket, overlapped plates pivotally connected to the rod and resting on the pulp carried by the belt, and a bolt extending through the overlapped portions of the plates for adjustably fastening said plates together.

7. The combination with a paper making machine including a pulp vat and an endless belt, of a ripple and bubble eliminator therefor, comprising U-shaped brackets extending over the gate of the vat, screws extending through the upper portions of the brackets and impinging against the gate for adjusting the height of the brackets, screws extending through other portions of the brackets and engaging the gate for clamping said brackets to the gate, a rod extending through lower outer portions of the brackets, hinge leaves pivotally and slidably adjustably mounted on the rod, a medial hinge leaf pivotally mounted on the rod, flanged overlapping plates connected to the slideable hinge leaves and having elongated registering openings, and a bolt

extending through said openings and the medial hinge leaf to secure the plates together in adjusted position.

8. The combination with a paper making machine including a pulp vat and an endless belt, of a ripple and bubble eliminator therefor, comprising U-shaped brackets extending over the gate of the vat, screws extending through the upper portions of the brackets and impinging against the gate for adjusting the height of the brackets, screws extending through other portions of the brackets and engaging the gate for clamping said brackets to the gate, a rod extending through lower outer portions of the brackets, hinge leaves pivotally and slidably adjustably mounted on the rod, a me-

dial hinge leaf pivotally mounted on the rod, flanged overlapping plates connected to the slideable hinge leaves and having 20 elongated registering openings, portions of said openings being of greater width than other portions, a bolt having an enlarged head for covering the lower opening and also having flattened side portions to prevent said bolt from turning in the openings, said bolt being removable through the opening portions of greater width, a washer covering the upper opening, and a nut threaded on the bolt to secure the plates 30 together in adjusted position.

In testimony whereof, I affix my signature.

RUSSELL M. PUTNAM.
